UNITED STATES PATENT OFFICE.

WILLIAM HUGHES, OF TAUNTON, MASSACHUSETTS, ASSIGNOR TO HUGHES EYELET COMPANY, OF TAUNTON, MASSACHUSETTS, A CORPORATION OF MAINE.

EYELET.

No. 872,237.

Specification of Letters Patent.

Patented Nov. 26, 1907.

Application filed April 16, 1907. Serial No. 368,538.

To all whom it may concern:

Be it known that I, WILLIAM HUGHES, of Taunton, in the county of Bristol and State of Massachusetts, have invented certain new and useful Improvements in Eyelets, of which the following is a specification.

This invention relates to an improved form of eyelet and comprises an eyelet, the marginal flange of which is slotted at a plurality of points forming a series of petals.

Figure 1, a top plan view, shows an eyelet constructed in accordance with my invention. Fig. 2 is a vertical section thereof on the line 2—2 of Fig. 1. Fig. 3, a top plan view of an eyelet constructed in accordance with my invention showing how the metallic head of the eyelet is protected by enamel or any desired substance. Fig. 4 is a vertical sectional view of the form of eyelet shown in Fig. 3, said view being taken on the line 4—4 of Fig. 3. Fig. 5 is a detail view showing the appearance of the eyelet in use.

1 represents a barrel of the eyelet formed at its lower end with scored lines or indentations 2 to weaken the barrel at this point and assist in the clenching process. The upper end of the barrel is formed with an outwardly turned flange 3, the edge of which is slotted at a plurality of points from the margin substantially to or near the barrel, forming a series of petals 4.

In the form of eyelet shown in Figs. 1 and 2, the head is not protected by any coating. In the form of eyelet shown in Figs. 3 and 4, the flange 3 and its petals 4 of the eyelet may be protected by a coating 5, of enamel or any desired substance. In Fig. 5, a portion of a

shoe upper 6, is shown provided with my improved eyelets.

My improved eyelet comprises a barrel 40 formed at its upper end with a series of independent petals. This construction facilitates the setting of the eyelet in the material without scarring since each individual petal in the setting operation can be seated upon 45 the material without reference to the other petals, so that foreign substance on the leather engaging one petal will not prevent an even setting of the balance of the other petals, as is the case where solid head eyelets 50 engage foreign substances, or uneven places on the leather, in which case, as will be evident, the part of the head of the eyelet engaging the foreign substance will prevent the balance of the head of the eyelet having 55 proper engagement with the material.

Having thus explained the nature of the invention and described a way of constructing and using the same, although without attempting to set forth all of the forms in 60 which it may be made, or all of the modes of its use, I declare that what I claim is:—

An eyelet comprising in its construction a barrel formed at its upper end with a series of independent petals, and having its lower 65 end adapted to be clenched upon the material to secure the eyelet in place.

In testimony whereof I have affixed my signature, in presence of two witnesses.

WILLIAM HUGHES.
